UNITED STATES PATENT OFFICE.

JOSEPH L. HERZOG, OF NEW ROCHELLE, NEW YORK.

DESIGN FOR A FINGER RING OR SIMILAR ARTICLE.

Application filed November 6, 1925. Serial No. 15,367. Term of patent 14 years.

To all whom it may concern:

Be it known that I, JOSEPH L. HERZOG, a citizen of the United States, and resident of New Rochelle, county of Westchester, State of New York, have invented a new, original, and ornamental Design for Finger Ring or Similar Article, of which the following is a specification.

The drawing is a perspective view of a finger ring embodying my design.

In the accompanying drawing forming part of the specification, the design is illustrated as embodied in a ring of the wed-

ding ring variety with the design engraved thereon. When the design has the dimensions such as are customary in rings and the metal is white gold or platinum color, the effect is not that of a series of flowers but closely approaches the effect of a series of glittering stones such as diamonds.

I claim:

The ornamental design for a finger ring or similar article substantially as shown and described.

JOSEPH L. HERZOG.
